MULTIPLE CONTROL SYSTEM AND METHOD OF MANUFACTURE THEREOF

Edward George Tronca, Milwaukee, Wis., assignor to Globe-Union Inc., Milwaukee, Wis., a corporation of Delaware

Filed Aug. 26, 1965, Ser. No. 482,859
11 Claims. (Cl. 317—99)

The present invention relates in general to multiple control systems and, more specifically, to electrical control systems including a plurality of tandem mounted control devices which are concurrently controlled by a single shaft and to the method of manufacturing such control systems.

In many present-day electrical and electronic applications, such as in stereophonic audio reproduction systems, multiple controllers or control systems are employed wherein a plurality of control devices, such as potentiometers, are mounted in tandem and are to be concurrently controlled by a single control shaft. Such control devices must be electrically matched in order to provide the desired multiple operation when controlled by a single control shaft. Various techniques are presently used in the matching of tandem mounted components such as potentiometers. In one technique, the resistance elements of the potentiometers are selected from the same batch or are formed from the same resistance strip. In a second technique, the overall resistances of resistance elements used in such potentiometers are measured and, if the resistances of the elements are substantially equal, the elements are assumed to have the same electrical characteristics and are employed in the tandem mounted potentiometers. In a third technique, the sloppiness in the mechanical fit between adjacent mounted control devices, such as potentiometers, is utilized and the control devices are offset relative to one another to provide the desired electrical matching. Such techniques have not proved to be entirely satisfactory and consequently it has been desirable to provide an improved multiple control system and improved method of manufacture thereof.

In accordance with the primary object of the present invention, a new and improved multiple control system is provided. More specifically, a new and improved electrical control system is provided which includes a plurality of tandem mounted control devices which are concurrently controlled by a single control shaft. In this connection, it is an object to provide a new and improved method of manufacturing such control systems.

A further object of the present invention is to provide a new and improved control system including a plurality of tandem mounted control devices which are concurrently controlled by a single shaft wherein the shaft is provided with a corresponding plurality of control portions and the shaft is formed so that the control portions may be offset relative to one another to match the control devices. Moreover, it is an object to provide a new and improved control shaft for use in multiple control systems. In this latter connection, it is an object to provide a new and improved control shaft having a plurality of control portions wherein the shaft is formed so that the control portions may be offset relative to one another.

A general object of the present invention is to provide a new and improved multiple control system, characterized in its simplicity and economy, which may readily be modified. A related object is to provide a new and improved control shaft for such a control system, likewise characterized in its simplicity and economy, which may readily be modified.

Other objects and advantages of the invention will become apparent upon reading the attached detailed description taken in conjunction with the drawing.

2

In one form of the present invention, a multiple control system is provided which includes a plurality of control devices mounted in tandem, the control devices having rotatable control elements and having apertures extending therethrough which are aligned. A shaft is provided which extends through the apertures and the shaft is formed with control portions which are keyed to and controllably engage the rotatable control elements so that the control elements are rotated concurrently with the shaft. The shaft is formed so that adjacent control portions thereof may be twisted relative to one another to offset the control portions relative to one another to match adjacent control devices. The invention also resides in the method of manufacturing such a multiple control system.

The present invention will now be described with reference to the drawing wherein:

FIGURE 1 is a sectional side elevational view of a multiple control system constructed in accordance with the teachings of the present invention;

FIGURE 2 is a view showing facing surfaces of a portion of the system shown in FIG. 1;

FIGURE 3 is a side view of a control shaft utilized in the system of FIG. 1 which is constructed in accordance with the teachings of the present invention; and

FIGURE 4 is a partial perspective view of the control shaft shown in FIG. 3 showing control portions thereof in offset positions.

While the invention has been shown and will be described in some detail with reference to a particular, exemplary embodiment thereof, there is no intention that it be limited to such detail. Quite to the contrary, it is intended here to embrace all the modifications, alternatives and equivalents falling within the spirit and scope of the invention as defined by the appended claims.

Referring now to the drawing and more specifically to FIG. 1, a multiple control system 10 is shown which is constructed in accordance with the teachings of the present invention. As may be seen, the exemplary control system 10 includes a pair of control devices 11 and 12 which are mounted in tandem, i.e., are mounted in piggy-back fashion, and which are disclosed as potentiometers. However, it will be readily apparent that a greater plurality of control devices may be mounted in tandem and control devices other than potentiometers may be mounted in tandem. For the purpose of allowing the control devices 11 and 12 to be connected together in tandem, a mounting plate 13 is suitably secured to the control device 12, such as by soldering, and has tabs 13a extending therefrom that are received in apertures within the main housing 11a of the control device 11. The tabs 13a are bent over as shown to secure the control devices 11 and 12 together.

Since the internal elements of the control devices 11 and 12 (FIGS. 1 and 2) are identical, corresponding numbers are given thereto. Each control device includes a terminal-resistance element assembly 14. The terminal-resistance element assembly 14 includes (1) a disc-like main body portion 14a which is generally formed of a relatively rigid plastic material such as a fibrous sheet impregnated with phenolic and which has a central circular aperture 14a' provided therein, (2) an annular conductive member 14b formed on the main body portion 14a, is electrically connected to a terminal 14c extending radially outwardly therefrom, and (3) an annular resistance element 14d which is electrically connected to a plurality of terminals 14e extending radially outwardly therefrom at spaced positions around the resistance element. For the purpose of completing an electrical circuit between the annular conductive member 14b and the resistance element 14d and thus for the purpose of completing an electrical circuit between terminal

14c and terminals **14e**, each control device is provided with a nonconductive rotatable control element **14f** having a spring-like wiper arm contact **14g** mounted thereon for resiliently engaging the contact member **14b** and a spring-like wiper arm contact **14h** mounted thereon for resiliently engaging the resistance element **14d**, the wiper arm contacts **14g** and **14h** being integrally formed and thus electrically connected together. It will be apparent that, as the control element **14f** of a control device is rotated, different resistances will be developed between terminal **14c** and the terminals **14e**. In order to limit the rotational movement of the control element **14f**, suitable stop means may be provided. Since the specific details of the control devices **11** and **12** do not constitute a portion of the present invention, further details thereof will not be set forth.

In accordance with the present invention, new and improved means are provided for concurrently rotating the rotatable elements **14f** and thus for concurrently varying the control devices **11** and **12**. For this purpose, a shaft **20** (FIGS. 1, 3 and 4) is provided which, in the exemplary arrangement, includes a main body portion **20a** and a pair of control portions **20b** and **20c**. The shaft **20** is formed with a reduced diameter at position **20d** intermediate the control portions **20b** and **20c** so that the control portions may be twisted relative to one another to offset positions as best seen in FIG. 4. As may be seen by reference to FIG. 1, the control portion **20b** controllably or drivingly engages the control element **14f** of the control device **11** because of the flat sides thereof and the corresponding keyed aperture in the control element **14f** so that the control element **14f** rotates with the shaft **20** and the resistance between selected terminals of the control device **11** may be controllably varied by rotating the shaft **20** a desired amount. In like manner, the control portion **20c** controllably or drivingly engages the control element **14f** of the control device **12** so that the control element **14f** rotates with the shaft **20** and the resistance between selected terminals of the control device **12** may be controllably varied by rotating the shaft **20** a desired amount. Thus, the control elements **14f** of the control devices **11** and **12** are concurrently rotated and the control devices **11** and **12** concurrently vary as rotational movement is imparted to the shaft **20**. As mentioned hereinabove, in many applications, the multiple control devices must be electrically matched. For this purpose with the exemplary control system **10** constructed in accordance with the teachings of the present invention, the control portions **20b** and **20c** of the shaft **20** are twisted relative to one another to offset positions whereby the control devices **11** and **12** in the exemplary arrangement are electrically matched.

A brief description of the method of constructing the assembly as shown in FIG. 1 may be helpful in understanding the present invention. The shaft **20** is formed with a main body portion **20a** and a pair of flat sided control portions **20b** and **20c** separated by an intermediate portion **20d** of reduced diameter which allows for twisting the control portions relative to each other to offset positions. The control devices **11** and **12** are then assembled on the shaft so that the shaft is received in aligned apertures extending therethrough and the control elements **14f** of the respective control devices **11** and **12** are controllably or drivingly engaged by the control portions **20b** and **20c** of the shaft **20**. The control assemblies **11** and **12** are connected together by inserting tabs **13a** of the mounting plate **13** through apertures in the main housing **11a** of the control device **11** and bending over the tabs **13a**. For the purpose of locking the control devices **11** and **12** in place on the shaft **20**, a lock ring **22** is positioned within a groove **20e** of the shaft **20**, the lock ring engaging the control element **14f** of control device **11**. The control devices **11** and **12** are then electrically matched by rotating the control element **14f** of device **11** and the associated control

portion **20b** relative to the control element **14f** of device **12** and the associated control portion **20c** so that the shaft **20** is twisted or cold worked at position **20d** and the control portions **20b** and **20c** are offset a prescribed amount relative to one another. As may be seen, the control portion **20c** extends through an aperture **12a** in the rear surface of the control device **12** so that the control portion **20c** may be gripped by a suitable tool for a twisting operation. On the other hand, the control portion **20b** is directly connected to main body portion **20a** of the shaft **20** so that the main body portion may be gripped by a suitable tool for a twisting operation. Thus, suitable tools may be associated with the control portions for effectively grippingly engaging the control portions so that they may be twisted relative to one another to the electrically matched positions. After such a matching operation, a cap **12b** may be suitably secured to the control device **12**, such as by soldering, to cover the exposed portion of the control portion **20c** to act as a dust shield and to prevent undesirable access to the control portion **20c**. Alternatively, a switch may be suitably secured to the control device **12**. Under such conditions, an appropriate opening is formed in the rear wall of the control device **12** and switch mechanisms are extended therethrough for engagement with appropriate actuator means formed on the control element **14f** (not shown). Since the details of the cap **12b** or switch do not constitute a portion of the present invention, further details thereof will not be set forth.

For the purpose of allowing for mounting of the assembly **10** on a panel or wall, a threaded mounting bushing **25** is suitably secured to the control device **11**, the main body portion **20a** of the shaft **20** extending through a corresponding bore **25a** in the bushing. The portion **20a** of the shaft **20** and the threaded portion of the bushing **25** may then be inserted through a corresponding aperture in a wall or panel and a nut may be threaded onto the threaded portion of the mounting bushing **25** to lock the assembly **10** in place on the panel or wall. The assembly **10** may then be controlled by imparting rotational movement to the shaft **20** so that the control devices **11** and **12** are concurrently varied.

In view of the foregoing, it will be apparent that a new and improved multiple control system has been provided which allows for matching a plurality of control devices which are concurrently varied or controlled. Moreover, it will be seen that a new and improved control shaft has been provided for use in connection with such a multiple control system. Finally, it will be seen that a new and improved method of manufacturing multiple control systems has been provided.

What is claimed is:

1. In a multiple control system, the combination which comprises a plurality of control devices mounted in tandem and having rotatable control elements, the control devices having apertures extending therethrough which are aligned and which define keyed apertures in the control elements, and a shaft extending through the apertures which is formed with control portions corresponding in number to the control devices for controllably engaging the keyed apertures of the rotatable control elements so that the elements are rotated concurrently with the shaft, said shaft including at least one portion between said control portions which is yieldable in torsion, means for angularly adjusting one portion of the shaft with respect to the other including portions at which said shaft may be engaged to enable said control portions to be rotated to permanently distort said portion.

2. In a multiple control system, the combination which comprises a plurality of electrical control devices mounted in tandem and having rotatable control elements, the control devices having apertures extending therethrough which define keyed apertures in the control elements, and a rotatable member extending through the apertures which is formed with control portions corresponding in

number to the control devices for controllably engaging the keyed apertures of the control elements so that the control elements are all rotated concurrently with the rotatable member, said rotatable member including at least one portion between said control portions which is yieldable in torsion, means for angularly adjusting one portion of the shaft with respect to another, including portions at which said shaft may be engaged to enable said control portions to be rotated to permanently distort said yieldable portion.

3. In a multiple control system, the combination which comprises a pair of electrical control devices mounted in tandem and having rotatable control elements, the control devices having aligned apertures extending therethrough which define keyed apertures in the control elements, and a shaft extending through the apertures which is formed with a pair of control portions for controllably engaging the control elements so that the control elements are rotated concurrently with the shaft, said shaft including a portion between said control portions which is yieldable in torsion, means for angularly adjusting one portion of the shaft with respect to another portion, including portions at which said shaft may be engaged to enable said control portions to be rotated to permanently distort said yieldable portion.

4. In a multiple control system, the combination which comprises a plurality of electrical control devices mounted in tandem and having rotatable control elements, the control devices having aligned apertures extending therethrough which define keyed apertures in the control elements, a common shaft extending through the apertures which has a plurality of control portions corresponding in number to the control devices for controllably engaging the keyed apertures of the control elements so that the control elements are rotated concurrently with the shaft, the shaft including at least one portion between said control portions which is yieldable in torsion, means for angularly adjusting one portion of the shaft with respect to another portion, including portions at which said shaft may be engaged to enable said control portions to be rotated, and means for allowing at least one of the control portions to be grippingly engaged so that they may be twisted relative to one another.

5. In a multiple control system, the combination which comprises at least two electrical control devices mounted in tandem and having rotatable control elements, the control devices having apertures extending therethrough which define keyed apertures in the control elements, and a shaft extending through the apertures which is formed with control portions corresponding in number to the control devices for controllably engaging the keyed apertures of the control elements so that the control elements are rotated concurrently with the shaft, the shaft having a reduced diameter, yieldable in torsion, to permit permanent distortion of the shaft intermediate the control

portions so that the control portions may be twisted to offset positions relative to each other to electrically match the control devices, and means for allowing the control portions to be effectively engaged so that they may be twisted relative to each other.

5 6. A shaft for concurrently controlling a plurality of control devices comprising a main body portion, a plurality of control portions for rigid attachment to parts of said control devices, and at least one portion between said control portions which is yieldable in torsion by twisting said control portions and means for permanently angularly displacing portions of the shaft.

10 7. The shaft claimed in claim 6 wherein said portion between said control portions has a thickness gradually decreasing from a maximum at points nearest said control portions.

15 8. A multiple control system having a plurality of control elements each including first and second portions rotatable relative to one another, a shaft passing through said control elements, said shaft being rotatable relative to said first portions and being attached to said second portions whereby said second portions rotate with said shaft, at least one of the portions of said shaft intermediate said second portions being yieldable in torsion by a twisting action to permanently distort the shaft, means for twisting portions of said shaft to angularly displace said portions and permanently distort the shaft.

20 9. The multiple control system of claim 8 wherein said yieldable portion includes a portion of reduced thickness between said second portions whereby said attached portions may be rotated relative to one another by twisting said shaft about said portion of reduced thickness.

25 10. The multiple control system of claim 9 wherein said reduced thickness portion comprises a section having a thickness gradually decreasing from a maximum at points nearest said attached portions.

30 11. The multiple control system of claim 10 wherein the second portions are keyed to said shaft.
